HARDWARE

Herbert W. Neunherz, Gardner, Mass.

Application December 24, 1940, Serial No. 371,555

3 Claims. (Cl. 287—20)

This invention relates to metal hardware and more particularly to fittings for the purpose of securing rods or like articles to a support.

Metal hardware applied to wooden elements, corners, and furniture in general, has the objection that parts of the hardware or fittings project through the furniture and otherwise present rough edges that have an unsightly appearance and may scratch or tear objects coming in contact therewith. These defects are especially objectionable in infants' cribs where any rough edges or corners of metal parts, such as screws, bolts, bushings, etc., mar the appearance of the crib and are very apt to scratch or cut the infant occupant of the crib as he moves about and attempts to climb up the sides of the crib in order to play or assist himself in standing; and also persons leaning over the sides of the crib to care for the infant are liable to be scratched, etc., by sharp edges and corners of the hardware.

Objects of this invention include the provision of means to obviate the above stated objections in metal hardware, and especially for infants' cribs; the provision of a fitting for the purpose described having no projecting rough parts or edges; the provision of a fitting which completely avoids any use of an application member extending all the way through its support but which still rigidly and securely holds its supported member to the base therefor; the provision of such a fitting comprising three separable parts, i. e., a spindle or bushing having two sockets at angles to receive a member to be supported and a screw to hold all the parts; and the provision of metal hardware comprising a fitting for the support of a rod or other article to a base, said fitting being ornamental in appearance, simple of application, economical in manufacture, and having no unsightly projecting parts or rough or sharp edges.

Other objects and advantages of the invention will appear hereinafter.

Reference is to be had to the accompanying drawing, in which

Fig. 1 is a view in elevation showing the application of the present invention to the guide rod for a drop side of an infant's crib;

Fig. 2 is a view partly in cross section showing the fitting comprising this invention in assembled relation;

Fig. 3 is an end view of Fig. 2, looking in the direction of arrow 3;

Fig. 4 is a view showing the individual parts of the fitting in disassembled relation;

Fig. 5 is a view partly in section of a modified form of the securing means; and

Fig. 6 is a view partly in section of a further modification thereof.

- 5 The fitting comprising the present invention may be used in any relation where desired or convenient but is illustrated in the present instance as forming a hanger or fitting for the support of the usual vertical guide for the drop side of an infant's crib.
- 10 Referring to Fig. 1, there is shown the vertical end post 10 of a child's crib, the usual drop side 12 and vertical guide 14 therefor. The guide 14 is supported at its upper end by a hanger or fitting generally indicated at 16 and which is the subject matter of the present invention. This fitting may, if desired, be duplicated at the lower end of the guide rod 14, as shown in Fig. 1, although other means may be 15 used for supporting the guide rod at its lower end, since the top end of the rod is located at a point where the child or others may be injured by the projecting ends of the ordinary guide hanger.
- 20 The fitting 16 embodies an ornamental turned spindle or bushing 18 of brass or other suitable metal. This bushing 18 is drilled or reamed centrally from end to end thereof, to provide the longitudinal bore or passage 20, and has an enlarged flat-faced flange 22 at one end and a rounded ball-like head 24 at the opposite end. The ball-like head 24 is machined off, as at 26, to provide a seat, the purpose of which is described below. The machined part 26 may be 25 slightly concave, as shown in Figs. 2 and 4. The ball-like head 24 is also drilled or reamed at right angles to the bore 20 to provide the larger diameter bore 28, the latter intersecting the bore 20 and passing through it slightly, as shown 30 at 30. The bore 28 is made of a size to closely and accurately receive an end of rod 14.
- 35 The vertical guide rod 14 is provided adjacent one end with a drilled hole 32 of the same diameter as the bore 20 so that this end of the guide rod 14 may be inserted in the bore 28 and the hole 32 is then alined with said bore 20 so as, in effect, to become a part thereof and continue the bore 20 from the machined surface 26 to the end of the flange 22.
- 40 There is also provided a through wood screw 34 which is placed through the hole 32 and the bore 20 so that the threads 36 extend beyond the flange 22. The screw 34 is provided with a rounded head 38 of the same curvature as the ball-like head 24 so that when the screw is po-

- 45 50 55

sitioned so that its head 38 contacts the machined area 26, the head 38 will complement the head 24 and take the place of the material machined therefrom so as to form a complete sphere. Any other shape desired may be utilized, such as ovate, square, hexagonal, etc.

In applying this fitting to a crib post or article of furniture, the flange 22 is placed flat against the surface from which the rod 14 is desired to be suspended. The drilled end of the rod 14 is then inserted in the bore 28, and the hole 32 aligned with the bore 20. The screw 34 is then inserted through the hole 32 and the bore 20, thus locking the parts together. The screw 34 is then turned to engage and enter the post 10, thus being securely anchored therein by the spiral threads 36, and the screw 34 being turned as far as possible, the fitting is firmly secured in place, the flat side of flange 22 being clamped flush with the surface of the post or support. The concavity of the machined area 26 permits a firm contact of the head 38 with the head 24 at all points so that there is no separation or crack between these parts.

If it is desired to use a machine screw in place of the wood screw 34, a tapped bushing 40 is inserted in a prepared hole in the post 10, and pins 42 are sunk into the sides of the post to engage in apertures in the sides of the bushing to hold the same in position, see Fig. 5. This is the only change necessary, except for the use of the machine screw 44, the spindle or bushing 18 being exactly the same as in the showing of Figs. 2 and 4. Of course the pins 42 could be replaced by a single pin extending completely through the bushing 40, it merely being necessary in such case to use a shorter thread on the machine screw 44. Also, an exteriorly threaded bushing 46, Fig. 6, may be screwed directly into a bore in post 10, if it is desired not to use pins 42, and in this case the same or other machine screw 44 may be utilized.

It will thus be seen that the means of anchoring or securing the fitting is completely concealed from view from all sides and there are no projecting parts of the anchoring means or of the fitting to scratch or injure the occupant of the crib or anyone leaning over the side of the crib. The head 38 of the screw 34 will be seen to be so shaped and formed that it virtually becomes a part of the ball-like head 24 and indistinguishable therefrom when the screw is completely seated in the post 10.

Having thus described my invention and the advantages thereof, I do not wish to be limited to the details herein disclosed, otherwise than as set forth in the claims, but what I claim is:

1. A hanger adapted to be secured to a support, comprising a tubular bushing having an enlarged rounded head at one end thereof, a bore extending through the bushing and head, said head having a flattened side oppositely located with respect to the bushing, a second bore located entirely within the head at an angle to said first named bore and intersecting and extending across the first named bore, said second bore intersecting the periphery of the head at one end only of the second bore, whereby said first named bore extends completely through the bushing, second bore, and head, and said second bore extends only partially through said head but completely across the first named bore; a rod having an end located in said second bore and crossing the first named bore, an elongated fastener extending through the first named bore and rod, a head at one end of said fastener rounded to conform to the shape of the first named head, and means at the other end of the fastener for entry in and connection to said support, whereby said fastener not only secures the rod to the bushing but both bushing and rod to said support.

2. In a device of the class described, a tubular bushing, an enlarged round head at one end of the bushing, a bore extending axially through the bushing and diametrically of the head and through the latter, a flattened area on said head, a second bore at right angles to the first named bore and located entirely within the head, said second bore intersecting the first bore and the periphery of the head at one end only of the second bore so as to form a pocket in the head, a rod having an aperture therethrough adjacent an end thereof, said end being located in said pocket with its aperture aligned with the first bore, and a fastener extending completely through the head and rod aperture, and through and beyond the bushing, said fastener having a rounded head having a center of curvature at the center of the round bushing head so that said heads cooperate to form a partial sphere with said fastener head seated on said flattened area, and means on said fastener at its end extending beyond the bushing for securing to a support, said fastener securing the rod, bushing, and itself to said support.

3. A device as recited in claim 1 wherein the fastener comprises a machine screw, in combination with a second bushing adapted to be located in a support and threaded to receive the screw, and means to retain the second bushing in said support.

HERBERT W. NEUNHERZ.
